DOUBLE-ACTING HINGE

Clemens W. Kujawa, Cudahy, Wis.

Application December 30, 1946, Serial No. 719,202

1 Claim (Cl. 16--163)

1. www.english-test.net/vocabulary/irregular_verbs/

1. Claim. (Cl. 16—163)

My invention refers to door hinges and it has for its primary object to provide a simple and effective double acting hinge for closures of all kinds, such as windows, articles of furniture, or the like. The hinge is especially applicable to household articles such as refrigerators that are usually positioned in confined or restricted space, where a one-way swing of the door is frequently awkward due to interference with other doors or articles of household use.

Another object of my invention is to provide hinges in upper and lower complementary pairs, having strap and leaf sections attached to the door and frame, with strap supports fixed to the door frame flush therewith whereby sagging of the door due to load strain is eliminated.

The strap element is equal in length to the width of the door having one of its leaves attached to the edge of the door while the opposite leaf is attached to the frame of the same.

With the above and other objects in view, which will appear as the description proceeds, the invention resides in the novel construction, combination and arrangement of parts, substantially as hereinafter described, and more particu-

ularly as hereinabove described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:

Figure 1 represents a face view of a refrigerator having a door in hinge connection therewith embodying the features of my invention.

Figure 2 is a fragmentary plan sectional view of the same, the section being indicated by line 2-2 of Figure 1.

Figure 3 is a similar plan sectional view upon another plane, the section being indicated by line 3-3 of Figure 1.

Figure 4 is a fragmentary cross sectional view through the upper hinge and associated elements, the section being indicated by line 4-4 of Figure 1, the door being shown in its closed position.

Figure 5 is a detailed cross sectional fragmentary view through the lower end of the door and refrigerator illustrating the door in its closed position.

Figure 6 is a perspective view of one of the hinge elements.

Referring by characters to the drawings, A

According to statements to the sheriff, the two men were in the city.

provided with a hinged leaf 1' secured to the door frame and a second leaf 1'' is secured to the juxtaposed edge of the door, it being understood that the two hinge leaves 1'' and 5'' are in axial alinement when the door is opened, as shown in Figure 1.

As indicated in full lines of Figures 2-5 inclusive, the door is shown in its closed position and in said position, the pairs of straps are nested and supported by the upper and lower rails 3 and 7 respectively.

From the foregoing description, as indicated in dotted lines of Figures 2 and 3 of the drawings, when the door C is swung from left to right, the straps 4 and 5 are carried out with the inner face of the door while the straps 2 and 7 remain nested and supported by the rails 3 and 8 flush with the face of the door frame.

When the door is swung in the opposite direction, from right to left, as indicated in dotted lines of Figures 2 and 3, the upper and lower straps 2 and 7, respectively, follow the inner face of the door while said door swings upon the strap hinge leaves 2' and 7' respectively.

Thus, it will be noted, that the door may be swung either to the right or to the left and in each instance its dormant associated strap element will be supported by the rails 3 and 8 respectively.

I claim:

In a receptacle having a door frame opening provided with a flat outer face and a double hinged door for the frame opening adapted to open from left to right and from right to left, the upper and lower corners of the frame opening being provided with aligned pairs of horizontally disposed slots, the lower slots being extended above the bottom of said receptacle, while the upper slots extend entirely below the top of the receptacle opening, a channel iron secured to the bottom of the lower slots, having its upper face flush with the bottom of said receptacle

opening, and a similar channel iron secured to the base of the upper slots, the channel irons being flush with the outer face of the receptacle frame, a pair of upper and lower left to right door opening straps extending across the door, each strap having a hinged leaf secured to the right hand wall of the receptacle, the said straps, at their opposite ends, being provided with hinged leaves secured to the opposite edges of the door, 10 the upper strap being aligned and adapted to be nested in the associated channel iron, and the lower strap being aligned with the top face of the lower channel iron, a pair of right to left door opening straps having hinge leaves secured to the left hand side wall of the receptacle, the lower strap being aligned and adapted to nest within the associated channel iron, each of the other ends of said straps having a hinged leaf secured to the opposite edges of the door, whereby when the door is opened from left to right, one of the lower hinge straps is nested within a channel iron to eliminate vertical movement of the door, and when said door is opened from right to left, one of the upper straps is nested within the associated channel iron to also eliminate vertical movement of the door, such vertical movements of said door being due to vertical up and down load pressure exerted upon the door.
